UNITED STATES PATENT OFFICE.

ROBERT T. MERRILL, OF MILWAUKEE, WISCONSIN.

VENTILATOR AND CHIMNEY-CAP.

1,326,523.

Specification of Letters Patent. Patented Dec. 30, 1919.

Application filed August 12, 1918. Serial No. 249,510.

To all whom it may concern:

Be it known that I, ROBERT T. MERRILL, a citizen of the United States, and resident of Milwaukee, Milwaukee county, Wisconsin,

5 have invented new and useful Improvements in Ventilators and Chimney-Caps, of which the following is a description, reference being had to the accompanying drawings, which are a part of this specification.

10 This invention has for its object to improve upon the ventilator and chimney cap construction covered by my United States Letters Patent No. 1,037,286, dated September 3, 1912, by providing additional deflec-

15 tors by means of the inner ends of the partitions or ribs to give an upward direction to the inflowing air and increase the inductive action upon the air or gas within the chimney or ventilator pipe.

20 Another object of the invention is to accomplish the improvements without materially increasing the cost of manufacture.

With the above and other objects in view the invention consists in the ventilator and 25 chimney cap as herein claimed and all equivalents.

Referring to the accompanying drawings in which like characters of reference indicate the same parts in different views:

30 Figure 1 is a sectional elevation of a ventilator and chimney cap constructed in accordance with this invention;

Fig. 2 is a plan view of the same inverted; and,

35 Fig. 3 is a detail view of one of the partitions or ribs showing in dotted lines the blank from which it is formed.

In these drawings 10 indicates a collar 40 adapted to be secured to a draft tube or pipe of a ventilator or chimney, having riveted to its upper edge a number of radially disposed vertical partitions or ribs 11. These partitions are set on an incline and are notched at their lower edges to fit on the

45 edge of the collar 10 and to form laterally bent ears 12 riveted to the collar on the outside thereof. An upper deflector ring 13 of the shape of a truncated cone is riveted to flanges 14 formed by bending up the upper

50 edges of the partitions 11, while a lower deflector ring 15 of somewhat similar shape is riveted to flanges 16 formed by bending up the lower edges of said partitions. While the inner diameter of the upper deflector ring 13 is preferably less than the diameter of the collar 10, as shown, the inner di-

ameter of deflector ring 15 is somewhat larger, leaving a space between them through which air may pass as indicated by arrows.

60 A conical fluted cap 17 is secured to the upper deflector ring 13 so that the fluted portions thereof form a series of inclined radial air passages 18.

In so far as described the construction does 65 not materially differ from that shown in my former patent referred to. It is, however, desirable to provide additional deflecting means for directing the air upwardly when it enters between the deflector rings and for 70 this purpose the end of the partition 11 is bent to one side to form a wing 19 meeting with and riveted to a similarly shaped wing 20 which projects in a similar manner from the next partition 11. Each partition 11 75 thus has one of the wings 20 riveted thereto for joining with the end 19 of the next partition to form a curved inclined deflector in the path of the current of air entering through the passageway between the partitions and between the deflector rings and directing it upwardly into the cap 17 and out through the passageways 18. This decidedly upward deflection of a strong current 80 of air causes a material influence on the suction exerted in the smoke pipe or ventilator by the inductive action, thus increasing the effectiveness of the device without materially adding to its cost.

85 Obviously the inclined deflectors may be formed otherwise than by the wings 19 and 20 but this is a most convenient construction and is at present preferred.

I desire it to be understood that this invention is not limited to any specific form 90 or arrangement of parts except in so far as such limitations are specified in the claims.

What I claim as new and desire to secure by Letters Patent is:

1. In a ventilator and chimney cap, having a collar, and a pair of conical rings connected by radial vertical partitions and mounted on the collar, the combination therewith of inclined deflectors above the interior of the collar and extending from 100 one partition to the next.

2. In a ventilator and chimney cap, having a collar, vertical partitions secured thereto and positioned radially thereon, and upper and lower deflector rings mounted on 105 the partitions, the combination therewith of inclined deflectors formed by the laterally

bent ends of the partitions and disposed above the interior of the collar and connecting with the next partitions.

3. In a ventilator and chimney cap, having a collar, radial partitions and conical deflector rings on the partitions, the combination of a wing on the inner end of each partition bent laterally toward the next partition, and having a wing attached to said next partition and bent laterally in the opposite direction and connected with the first mentioned ring forming together an inclined deflector above the interior of the collar.

4. In a ventilator and chimney cap, having a collar, a pair of spaced conical rings

connected and supported by radial vertical partitions secured to the collar, the lower ring being concentrically disposed with respect to said collar with its inner periphery spaced therefrom, the combination therewith of deflector plates carried by said partitions and projecting inwardly above the top of the collar. 20

In testimony whereof I affix my signature in presence of two witnesses.

ROBERT T. MERRILL.
